UNITED STATES PATENT OFFICE.

HENRY L. FERRIS, OF HARVARD, ILLINOIS, ASSIGNOR TO HUNT-HELM FERRIS & CO., OF HARVARD, ILLINOIS, A CORPORATION OF ILLINOIS.

HOG-PEN.

1,239,170.

Specification of Letters Patent.

Patented Sept. 4, 1917.

Application filed November 9, 1916. Serial No. 130,431.

To all whom it may concern:

Be it known that I, HENRY L. FERRIS, a citizen of the United States, residing at Harvard, in the county of McHenry and 5 State of Illinois, have invented a new and useful Improvement in Hog-Pens, of which the following is a specification.

My invention relates to certain new and useful improvements in hog-pens, and is 10 fully described and explained in the specification and shown in the accompanying drawings, in which:

Figure 1 is an elevation of the improved pen; Fig. 2 is a section on the line 2 of Fig. 15 1, showing the guard swung back; Fig. 3 is a section on the line 3 of Fig. 1, showing the guard in normal position and the trough elevated; Fig. 4 is a section on the line 4 of Fig. 1; Fig. 5 is an elevation similar to 20 Fig. 1 of a modified construction, and Fig. 6 is a section on the line 6 of Fig. 5.

Referring to the drawings, 7 is a curb, preferably of concrete, to which are secured in any appropriate manner posts 8 connect- 25 ed by a top rail 9 and having at their lower ends forwardly extending brackets 10 forming horizontal bearings in which is rotatably mounted a rock-shaft 11. Hung from the top rail 9 is a swinging guard 30 comprising a top bar 12, bottom bar 13 and vertical tubes 14. The top and bottom bars 12 and 13 of the guard are preferably square in cross-section and the vertical bars of the 35 guard are preferably passed through openings in the bottom and top faces of the top and bottom bars, respectively, to bear against the opposite surfaces of said bars and the whole guard being held together by bolts 15 passed through certain of the 40 vertical bars and through perforations in the top and bottom bars. This method of construction is exceedingly simple and convenient, it permits quick assembling and produces at the minimum cost a very rigid 45 guard structure.

The rock-shaft 11 has secured to its arms 16, bifurcated at their upper ends to receive pivotally, in holes in their furcations, gudgeons 16^a on collars 17 vertically slide- 50 able upon certain of the vertical bars of the guard. The furcations of the arms 16 also receive pivotally between them the lower end of a pull rod 18 having at its upper end a handle 19 and a guide-ring 20 which surrounds the corresponding vertical

bar of the guard. In the structure herein illustrated two arms 16 with their connec- 5 tions are mounted upon the rock-shaft 11. They both necessarily move together, and are employed in the duplicate relation to 30 secure even application of force at both ends of a comparatively long guard.

The guard is normally held in its outward or closed position by a hook 21 which en- 65 gages the rock-shaft, as shown in Fig. 4, and which can be pulled up to release the guard by means of a button 22 running in a slot in the upper end of one of the vertical bars of the guard and connected by a rod or wire with the hook 21.

23 is a feed trough which is made of metal and is pivoted to brackets 24 secured to the curb so that it can be swung from its lowered position, as shown in Fig. 2, to the elevated position, shown in Fig. 3. When 70 in use it occupies the lowered position and it is swung up to dump most of its contents, and to take a position where it can readily be washed out. The trough is held in its upper position by a hook 25 pivoted to a 75 bracket 26 on one of the vertical bars of the guard. The hook has an upward extension formed into an oval ring 27 surrounding the vertical bar of the guard and permitting the requisite play to the hook, while at the 80 same time furnishing a very secure support for the hook upon the bar.

The operation of the preferred device so far explained is relatively simple. It is found in practice difficult to handle hogs 90 while the trough is being filled, not only because the trough is normally inside of the pen and inaccessible, but because the hogs crowd and push into the trough while it is being filled. The pivoted guard here shown 95 obviates this difficulty. Before feeding the hogs the trough is pushed down into its normal or lowered position, the button 22 is operated to raise the hook 21 and free the guard and the guard is then swung into the 100 position shown in Fig. 2 over the trough, so as not only to keep the hogs from the trough, but to make the trough readily accessible from without the pen. As the guard swings in, the arms 16 swing down until they finally 105 move to and slightly beyond a position at right-angles to the guard. In other words, the brace-arms have swung slightly past the dead center and, of course, lock the guard firmly in its inner position. The trough is 110

then filled and the guard swung back by pulling up on the handle 19 which raises the brace-arms 16 and automatically returns the guard. The guard can be swung back, 5 in the first instance, either by pushing down on this same handle or it might be pushed in by the foot of the operator. In the former case, the button by which the locking hook 21 is controlled is within easy reach of 10 the operator who is at the same time holding the handle 19. After the trough has been emptied, it may be swung up and washed out as hereinbefore indicated.

The preferred form of construction having the rock-shaft and the duplicate brace-arms 16 is the more desirable where the pen is a large one and the guard is therefore of 15 considerable length. The pressure which a hog exerts against the guard in trying 20 to get at the food in the trough may be very heavy and with a long guard it is important that it be braced inward at two points near the ends so that a twisting force can not be set upon it. When a pen is smaller, 25 however, and a shorter guard can be used, the balanced bracing is of less importance and the simpler structure of the modified form can be adopted.

Referring now to Fig. 5 the construction 30 is precisely the same as that shown in the other figures, except that there is only a single arm 16, this being pivotally mounted upon a central bracket 28 on the curb. The operating handle for the brace 16 is omitted in this 35 form of construction and the guard is locked in its normal position by a hook 29 pivoted to its bottom bar and engaging a laterally extending pin 30 on the arm 16 and extending sufficiently forward therefrom that it 40 can be operated by the foot. This structure is operated, in general, the same way as the preferred structure but with this difference. The guard is released by raising the hook 29, commonly by the toe of the operator and 45 the guard is then pressed in either by hand or by the foot of the operator resting on its bottom bar or on the arm 16. When it is desired to return the guard to normal position the arm is simply swung up either by 50 the toe of the operator or by hand and the guard swings shut principally by gravity.

I realize that considerable variation is possible in the details of this construction without departing from the spirit of my invention; therefore I do not intend to limit 55 myself to the specific form herein shown and described except as pointed out in the following claims, in which it is my intention to claim all the novelty inherent in the construction as broadly as is permitted by the state of the art.

What I claim as new and desire to secure by Letters Patent is:

1. In combination, a curb, a frame mounted on the curb, a trough pivoted to the rear

of the curb, a guard comprising vertical and top and bottom members and hung from a horizontal pivot in front of the trough and adapted to be swung back over the same to prevent access thereto from the rear and to afford access thereto from the front, and a pivoted arm mounted on the frame and engaging one of the vertical members of the guard on a vertically movable pivot thereon and arranged to swing past the dead-center 75 when the guard is in its rear position to hold the same.

2. In combination, a curb, a frame mounted on the curb, a trough pivoted to the rear of the curb, a guard comprising vertical and top and bottom members and hung from a horizontal pivot and normally in front of the trough and adapted to be swung backward over the same to cut off access thereto from the rear and provide access thereto 85 from the front, a member vertically slidable on one of the vertical members of the guard, and a stationarily pivoted arm mounted on the frame and engaging said slidale member and arranged to swing past the dead-center 90 to lock the guard in its rear position.

3. In combination, a curb, a frame mounted on the curb, a trough pivoted to the rear of the curb, a guard comprising vertical and top and bottom members and hung from a horizontal pivot in front of the trough and adapted to be swung backward over the same to prevent access thereto from the rear and afford access thereto from the front, a pivoted arm mounted on the frame and engaging one of the vertical members of the guard on a moving pivot and arranged to swing past the dead-center when the guard 95 is in its rear position to hold the same, and means for locking the guard in its normal 100 position.

4. In combination, a curb, a frame mounted on the curb, a trough pivoted to the rear of the curb, a guard comprising vertical and top and bottom members and hung from a horizontal pivot in front of the trough and adapted to be swung backward over the same to prevent access thereto from the rear and afford access thereto from the front, a pivoted arm mounted on the frame and engaging one of the vertical members of the guard on a moving pivot and arranged to swing past the dead-center when the guard is in its rear position to hold the same, and a hook 110 movably mounted on the guard and operating to hold the guard in its normal position.

5. In combination, a trough, a guard hung from a horizontal pivot and normally in front of the trough and adapted to swing backward over the trough to afford access thereto from the front and to prevent access thereto from the rear, a rock-shaft, and a plurality of arms carried by the rock-shaft and engaging the guard on vertically movable pivots thereon and movable in unison 115 120 125 130

- past the dead center to hold the guard in its rearward position.
6. In combination, a curb, a frame mounted on the curb, a trough pivoted at the rear 5 of the curb, a pivoted guard hung from a horizontal pivot and normally lying in front of the trough and arranged to be swung rearward over the trough to afford access thereto from the front and cut off access thereto from the rear, means for locking the guard in its forward and rear positions, and means on the guard for engaging the trough 10 when swung up to hold the same toward the guard with its interior facing forward.
- 15 7. In combination, a curb, a frame mount-
- ed on the curb, a trough pivoted to the rear of the curb, a guard comprising vertical and top and bottom members and hung by a pivot at its top and normally depending above and in front of the trough and adapted to be swung backward over the trough to afford access thereto from the front and cut off access thereto from the rear, and a pivoted arm mounted on the frame and engaging one of the vertical members of the guard 20 on a shiftable pivot thereon and operating as a dead-center lock to hold the same open.
- 25

In testimony whereof, I have hereunto set my hand this 30th day of October, 1916.

HENRY L. FERRIS.
